(57) **CLAIM**

The ornamental design for a nasal dilator, as shown and described.

DESCRIPTION

FIG. 1 is a perspective view of a nasal dilator showing our new design;

FIG. 2 is an enlarged view of the left side of the nasal dilator shown in FIG. 1 taken along line 2;

FIG. 3 is an enlarged view of the right side of the nasal dilator shown in FIG. 1 taken along line 3;

FIG. 4 is a front view of the nasal dilator shown in FIG. 1; FIG. 5 is an enlarged view of the left side of the nasal dilator shown in FIG. 4 taken along line 5;

FIG. 6 is an enlarged view of the right side of the nasal dilator shown in FIG. 4 taken along line 6;

FIG. 7 is a back view of the nasal dilator shown in FIG. 1; FIG. 8 is an enlarged view of the left side of the nasal dilator shown in FIG. 7 taken along line 8;

FIG. 9 is an enlarged view of the right side of the nasal dilator shown in FIG. 7 taken along line 9;

FIG. 10 is a top view of the nasal dilator shown in FIG. 1; FIG. 11 is an enlarged view of the left side of the nasal dilator shown in FIG. 10 taken along line 11;

FIG. 12 is an enlarged view of the right side of the nasal dilator shown in FIG. 10 taken along line 12;

FIG. 13 is an enlarged end view of the left side of the nasal dilator shown in FIG. 1; and,

FIG. 14 is an enlarged end view of the right side of the nasal dilator shown in FIG. 1.
